OXIDATION OF 2,5-DIALKYL PYRIDINES

Milton E. Abraham, Cresskill, N.J., and Godfrey Wilbert, Carmel, N.Y., assignors, by mesne assignments, to Warner-Lambert Pharmaceutical Company, Morris Plains, N.J., a corporation of Delaware

No Drawing. Application December 1, 1955
Serial No. 550,486

4 Claims. (Cl. 260—295.5)

This invention relates to the oxidation of 2,5-dialkyl pyridine compounds and relates more particularly to an improved catalytic process for the nitric acid oxidation of 2-methyl-5-ethyl pyridine.

Pyridine carboxylic acids such as niacin and isocinchomeric acid have been obtained by the controlled oxidation of alkyl pyridine compounds. The alkyl pyridines which have been utilized in this oxidation process include the picolines and lutidines. Pyridine compounds containing longer-chain alkyl substituents have also been found satisfactory for use in this process, particularly 2-methyl-5-ethyl pyridine. The catalytic nitric acid oxidation of 2-methyl-5-ethyl pyridine has been suggested, and the reaction conditions recommended for carrying out this particular process have included the use of aqueous nitric acid of from 5 to 40% concentration and temperatures up to about 220° C. Others who have been concerned with this reaction have proposed the use of nitric acid of a concentration of 40 to 95% and temperatures of up to 200° C., the reaction being carried out under pressures as high as 700 p.s.i.g. While the yields obtained under these conditions are appreciable they have not been higher than about 70% of theoretical. Higher yields have been obtained by relying upon the use of substantial, at least stoichiometric, amounts of copper during the oxidation reaction so that the copper salts of the carboxylic acids formed are obtained and are thus separated from the reaction. Although high yields are obtainable, the latter expedient is quite cumbersome, process-wise, since it entails breaking up the copper salt before the free acids may be obtained.

Another disadvantageous factor in the processes heretofore employed for the oxidation of 2,5-dialkyl pyridines is that the reaction mixture obtained after the completion of the oxidation reaction consists of a relatively concentrated nitric acid solution usually containing at least 10% by weight of nitric acid. Since niacin is quite soluble in nitric acid of this concentration the separation of this product first required neutralization of the unreacted nitric acid with an alkaline agent. Under these conditions not only was the cost increased because of the necessity for using a neutralizing agent but the nitrate salts thus formed further complicated the separation of the niacin.

It is, therefore, an important object of this invention to provide an improved process for the nitric acid oxidation of a 2,5-dialkyl pyridine whereby niacin and isocinchomeric acid are obtained in greatly improved yield.

Another object of this invention is the provision of an improved, continuous process for the catalytic, nitric acid oxidation of 2,5-dialkyl pyridines to form niacin and isocinchomeric acid wherein said reaction products are more readily separated from the reaction mixture without excessive loss or consumption of nitric acid.

Other objects of this invention will appear from the following detailed description.

We have now found that improved yields of niacin and isocinchomeric acid are obtained when oxidizing a

2

2,5-dialkyl pyridine with nitric acid, if the oxidation is carried out at a temperature of at least 250° C. and under a pressure of at least 750 pounds per square inch gauge, employing a soluble salt of iron as catalyst. The use of catalytic amounts of iron and of high pressure, in conjunction with temperatures higher than heretofore employed when carrying out said oxidation reaction, has been found to give yields of niacin and isocinchomeric acid of as high as 98% of theory, which is considerably higher than has been previously obtained.

In carrying out our novel oxidation process, we may employ any 2,5-dialkyl pyridine such as 2,5-dimethyl pyridine or 2-methyl-5-ethyl pyridine, for example. The latter is preferred since it is readily available from synthetic procedures and in any desired quantities.

The nitric acid concentration we employ for carrying out said catalytic oxidation may be from 5 to 40% by weight. The nitric acid in the reaction mixture is preferably employed in a ratio of at least 5.5 mols of nitric acid for each mol of 2,5-dialkyl pyridine. The reaction is preferably carried out in a reaction zone of relatively small cross-section so that proper temperature control of the reaction mixture may be obtained. The reaction is exothermic and by counter current flow the entering reaction mixture may be heated rapidly to the desired temperature by the heat from the catalytic nitric acid oxidation of the 2,5-dialkyl pyridine already in the reaction zone. The iron catalyst may be present in an amount of from 0.01 to 0.2 mol for each mol of 2,5-dialkyl pyridine in the reaction mixture and is preferably employed in a ratio of 0.05 mol for each mol of the 2,5-dialkyl pyridine.

While the reaction temperature should be at least 230° C., temperatures as high as 350° C. may also be satisfactorily employed.

The pressure maintained in the reaction zone should be at least 750 pounds per square inch gauge and may be as high as 2500 pounds per square inch gauge. Usually, pressures of about 800 to 900 pounds per square inch are satisfactory.

Ordinarily, the reactants are maintained under these reaction conditions for from 25 to 600 seconds to effect the desired oxidation before being cooled below reaction temperature to prevent excessive oxidation.

Preferably, at least partial cooling is effected by flashing the reaction mixture so that the pressure is reduced rapidly from that maintained during the oxidation reaction to atmospheric or substantially atmospheric pressure, that is to from 0 to 150 p.s.i.g. Cooling the reaction mixture in this way is quite effective and is highly advantageous in making the separation of the oxidation products simpler and more economical. By flashing the reaction mixture, substantially all of the nitric oxide is separated as a vapor. The substantial reduction in the concentration of the nitric acid, to no more than 1% by weight, makes the niacin and isocinchomeric acid formed far easier to separate since they are less soluble in such dilute nitric acid than in the more concentrated acid comprising the nitric acid oxidation medium. The nitric oxide flashed over passes to a recovery system where it is absorbed in water and the nitric acid formed is brought up to the strength or concentration desired.

In order further to illustrate our invention but without being limited thereto, the following examples are given:

Example I

An aqueous reaction mixture consisting of 10 parts by weight of 2-methyl-5-ethyl pyridine, 31 parts by weight of nitric acid, 0.075 part by weight of iron (as ferric nitrate) and 59 parts by weight of water are passed into a reactor at a pressure of 820 pounds per square inch

gauge, and while under this pressure the mixture is heated to a temperature of 256° C. The rate of flow through the reactor is adjusted so that the mixture is maintained at this temperature and pressure for about 130 seconds. After the desired oxidation of the 2-methyl-5-ethyl pyridine to niacin and isocinchomeric acid has taken place the mixture is discharged to atmospheric pressure and the nitric oxide flashes off to a recovery system. The conversion of 2-methyl-5-ethyl pyridine to niacin and isocinchomeric acid is 76.8% and an unreacted 21.2% is recovered.

Example II

An aqueous reaction mixture consisting of 10 parts by weight of 2-methyl-5-ethyl pyridine, 31 parts by weight of nitric acid, 0.075 part by weight of iron (as ferric nitrate) and 59 parts by weight of water are passed into a reactor at a pressure of 900 p.s.i.g., and while under this pressure is heated to a temperature of 256° C. The rate of flow through the reactor is adjusted so that the mixture is maintained at this temperature and pressure for about 320 seconds. After the desired oxidation of the 2-methyl-5-ethyl pyridine to niacin and isocinchomeric acid has taken place, the mixture is discharged to atmospheric pressure and the nitric oxide present flashes off to a recovery system. The conversion of 2-methyl-5-ethyl pyridine to niacin and isocinchomeric acid is 86%. 9.9% of the 2-methyl-5-ethyl pyridine is recovered.

Example III

An aqueous reaction mixture consisting of 10 parts by weight of 2-methyl-5-ethyl pyridine, 31 parts by weight of nitric acid, 0.075 part by weight of iron (as ferric nitrate) and 59 parts by weight of water are passed into a reactor at a pressure of 1250 p.s.i.g., and while under this pressure is heated to a temperature of 266° C. The rate of flow through the reactor is adjusted so that the mixture is maintained at this temperature and pressure for about 550 seconds. After the desired oxidation of the 2-methyl-5-ethyl pyridine to niacin and isocinchomeric acid has taken place the mixture is discharged to atmospheric pressure and the nitric oxide flashes off to a recovery system. The conversion of 2-methyl-5-ethyl pyridine to niacin and isocinchomeric acid is 77.2%. 12.4% of the 2-methyl-5-ethyl pyridine is recovered.

Example IV

An aqueous reaction mixture consisting of 10 parts by weight of 2-methyl-5-ethyl pyridine, 31 parts by weight of nitric acid, 0.075 part by weight of iron (as ferric nitrate) and 59 parts by weight of water are passed into a reactor at a pressure of 1200 p.s.i.g., and while under this pressure is heated to a temperature of 270° C. The rate of flow through the reactor is adjusted so that the mixture is maintained at this temperature and pressure for 400-500 seconds. After the desired oxidation of the 2-methyl-5-ethyl pyridine to niacin and isocinchomeric acid has taken place the mixture is discharged to atmospheric pressure and the nitric oxide flashes off to a recovery system. About 8.84% of the 2-methyl-5-ethyl pyridine is unreacted and is recovered. The nitric oxide flashed off reduces the nitric acid content of the reaction medium to less than 1%.

It is understood that the foregoing detailed description is given merely by way of illustration and that many variations may be made therein without departing from the spirit of our invention.

Having described our invention, what we desire to secure by Letters Patent is:

1. In a process for the oxidation of a 2,5-di-lower alkyl pyridine to niacin and isocinchomeric acid, the steps

which comprise forming a reaction mixture containing from 1 to 15% by weight of said dialkyl pyridine, at least 5.5 mols of aqueous nitric acid of a concentration of 5 to 40% by weight for each mol of 2,5-dialkyl pyridine, and from 0.01 to 0.2 mol of iron, as a nitric acid soluble iron compound, passing the mixture through a reaction zone while at a temperature of at least 250° C. and under a pressure of at least 750 p.s.i.g., removing the resulting reaction mixture from the reaction zone, cooling the mixture by reducing the pressure to atmospheric, flashing nitric oxide off and reducing the nitric acid in said reaction mixture to not more than about 1% by weight, and separating niacin and isocinchomeric acid therefrom.

5 2. In a process for the oxidation of a 2,5-di-lower alkyl pyridine to niacin and isocinchomeric acid, the steps which comprise forming a reaction mixture containing from 1 to 15% by weight of said dialkyl pyridine, at least 5.5 mols of aqueous nitric acid of a concentration

10 of 5 to 40% by weight for each mol of 2,5-dialkyl pyridine, and from 0.01 to 0.2 mol of iron, as iron nitrate, passing the mixture through a reaction zone while at a temperature of at least 250° C. and under a pressure of at least 750 p.s.i.g., removing the resulting reaction mixture

25 from the reaction zone, cooling the mixture by reducing the pressure to atmospheric, flashing nitric oxide off and reducing the nitric acid in said reaction mixture to not more than about 1% by weight, and separating niacin and isocinchomeric acid therefrom.

30 3. In a process for the oxidation of 2-methyl-5-ethyl pyridine to niacin and isocinchomeric acid, the steps which comprise forming a reaction mixture containing from 1 to 15% by weight of said 2-methyl-5-ethyl pyridine, at least 5.5 mols of aqueous nitric acid of a concentration

35 of 5 to 40% by weight for each mol of 2-methyl-5-ethyl pyridine, and from 0.01 to 0.2 mol of iron, as a nitric acid soluble iron compound, passing the mixture through a reaction zone while at a temperature of at least 250° C. and under a pressure of at least 750 p.s.i.g., removing the resulting reaction mixture from the reaction zone, cooling the mixture by reducing the pressure to atmospheric, flashing nitric oxide off and reducing the nitric acid in said reaction mixture to not

40 more than about 1% by weight, and separating niacin and isocinchomeric acid therefrom.

45 4. In a process for the oxidation of 2-methyl-5-ethyl pyridine to niacin and isocinchomeric acid, the steps which comprise forming a reaction mixture containing from 1 to 15% by weight of said 2-methyl-5-ethyl pyridine, at least 5.5 mols of aqueous nitric acid of a concentration of 5 to 40% by weight for each mol of 2-

50 methyl-5-ethyl pyridine, and from 0.01 to 0.2 mol of iron, as iron nitrate, passing the mixture through a reaction zone while at a temperature of at least 250° C. and under a pressure of at least 750 p.s.i.g., removing the resulting reaction mixture from the reaction zone, cooling the mixture by reducing the pressure to atmospheric, flashing nitric oxide off and reducing the nitric acid in

55 the nitric acid in said reaction mixture to not more than about 1% by weight, and separating niacin and isocinchomeric acid therefrom.
